UNITED STATES PATENT OFFICE

FERDINAND S. BARBIERS, OF LANCASTER, OHIO, ASSIGNOR TO THE DIAMOND MATCH COMPANY, OF BALTIMORE, MARYLAND, A CORPORATION OF MARYLAND

DESIGN FOR A COMBINED MATCH AND ASH TRAY OR SIMILAR ARTICLE

Application filed January 31, 1933. Serial No. 47,060. Term of patent 7 years.

To all whom it may concern:

Be it known that I, FERDINAND S. BARBIERS, a subject of the King of Belgium, residing at Lancaster, in the county of Fairfield and State of Ohio, have invented a new, original, and ornamental Design for a Combined Match and Ash Tray or Similar Article, of which the following is a specification, reference being had to the accompanying drawing, forming part thereof.

The figure is a perspective view of a match and ash tray showing my new design, the essential feature of which is the ornamental matter on the body of the tray or similar article.

I claim—

The ornamental design for a combined match and ash tray or similar article as shown and described.

FERDINAND S. BARBIERS.
